(57) **CLAIM**

The ornamental design for an ambidextrous glove with gripper tread, as shown and described.

DESCRIPTION

FIG. 1 is a front elevation view showing the new, original, and ornamental design of an ambidextrous glove with gripper tread;

FIG. 2 is a rear elevation view thereof;

FIG. 3 is a left side elevation view thereof;

FIG. 4 is a right side elevation view thereof;

FIG. 5 is a bottom plan view thereof; and,

FIG. 6 is a top plan view thereof.

The broken lines shown in the drawings represent environmental subject matter and form no part of the claimed design.
